ELECTRIC CAN OPENER

Henry J. Talge, Kansas City, and Joseph L. Grant and
William A. Chappell, Raytown, Mo., assignors to Rival
Manufacturing Company, a corporation of Missouri

Filed Aug. 7, 1961, Ser. No. 66,220

Term of patent 14 years

(Cl. D22—2)

Fig. 1.

Fig. 2.

Fig. 3.

Fig. 4.

FIG. 1 is a front elevational view of an electric can opener embodying our new design;

FIG. 2 is a side elevational view of same taken from the right-hand side of FIG. 1;

FIG. 3 is a top plan view of same; and

FIG. 4 is a fragmentary side elevational view of same taken from the left-hand side of FIG. 1, the part not shown in FIG. 4 being substantially identical to the lower portion of the side shown in FIG. 2.

We claim:

The ornamental design for an electric can opener, as shown and described.
